Des. 194,611

Patented Feb. 19, 1963

194,611

FISHING ROD HOLDER

Otis V. Faulkner, 205 McGowen, Houston, Tex.

Filed Sept. 29, 1961, Ser. No. 66,905

Term of patent 14 years

(Cl. D31—4)

FIG. 1 is a side elevational view of a fishing rod holder, showing my new design; and,

FIG. 2 is a top plan view thereof.

I claim:

The ornamental design for a fishing rod holder, as shown.
